(57) **CLAIM**

The ornamental design for a tire tread, as shown and described.

DESCRIPTION

FIG. 1 is a perspective view of the tire tread showing my design;

FIG. 2 is a front view thereof;

FIG. 3 is a rear view thereof;

FIG. 4 is a right side view thereof;

FIG. 5 is a left side view thereof;

FIG. 6 is an enlarged detail view thereof; and,

FIG. 7 is a sectional view thereof.

The broken lines are used to show portions of the tire tread that are not being claimed, and thus form no part of the claimed design.
